GARMENT HANGER

Reynolds Guyer, St. Paul, Minn., assignor to
 Waldorf Paper Products Company, St. Paul,
 Minn., a corporation of Minnesota

Application January 17, 1938, Serial No. 185,381

9 Claims. (Cl. 223—88)

My invention relates to garment hangers constructed of paper and having a frame provided with a cross frame member and two side frame members pivoted thereto and adapted to be connected together at their free ends, and particularly to garment hangers constructed from strips of paper bent to form flanges at the free ends of the side frame members.

5

An object of the invention resides in providing 10 a hook or supporting member attached to the free ends of the side frame members and holding the same in position.

Another object of the invention resides in constructing the hook so that, when properly applied, the side frame members are securely held 15 from disengagement.

A still further object of the invention resides in providing a construction by means of which 20 the hook may be easily and quickly attached to the side frame members.

Another object of the invention resides in providing a hook constructed of relatively light wire 25 and in forming the hook so that the same will offer an appreciable resistance to straightening out when the loaded hanger is subjected to repeated shocks.

Other objects of the invention reside in the 30 novel combination and arrangement of parts and in the details of construction hereinafter illustrated and/or described.

In the drawing:

Fig. 1 is a perspective view of a garment hanger illustrating an embodiment of my invention.

35 Fig. 2 is a fragmentary sectional view taken on line 2—2 of Fig. 1 and showing the manner of applying the hook.

Fig. 3 is a fragmentary sectional view, similar to Fig. 2, taken on line 3—3 of Fig. 1 and showing 40 the hook in a different position.

Fig. 4 is a fragmentary plan sectional view taken on line 4—4 of Fig. 3.

Fig. 5 is a perspective view of the hook.

Fig. 6 is a fragmentary elevational view of the 45 hook and side frame members showing the hanger supported on a cylindrical rod.

In the use of garment hangers, constructed 50 from paper and having a separate metal hook formed of wire, it becomes desirable to hold the hook from movement relative to the side frame members. The present invention overcomes this difficulty by providing a construction whereby the hook may be rigidly attached to the side frame members. With such types of garment hangers considerable difficulty is encountered in

threading the hook through the flanges of the side frame members. The present invention overcomes this difficulty by providing a clip having twisted reaches adapted to permit of twisting the hook, as the same is applied, to facilitate the attachment of the hook to the garment hanger. Where shocks are repeatedly given to a garment hanger, as where the loaded hanger is transported in an automobile, the hook portion frequently straightens out and causes the garment hanger to become disengaged therefrom. 5 The present invention overcomes this difficulty by constructing the hook portion with a bight which is located to one side of the vertical medial plane of the support where greater rigidity is procured 10 than where a uniformly curved hook is employed or a hook with a bight at the center of the same is employed.

The garment hanger illustrated, comprises a frame 10, constructed with a cross frame member 11 and two side frame members 12 and 13. The frame members 12 and 13 are hingedly connected to the frame member 11 and are adapted to be folded into substantial alignment with said cross frame members when collapsed, or to be 15 extended obliquely therefrom when in operative position, as illustrated in Fig. 1, in which case 20 said frame members converge. These frame members are longer than one-half the length of the cross frame member 11 so that said frame 25 members become disposed in the form of a triangle when erected.

The garment hanger further includes a hook or supporting member 14 by means of which the 30 hanger is supported and which is attached to the ends of the side frame members 12 and 13.

The frame 10 is constructed from paper which is folded in the manner shown to provide the cross frame member 11 with flanges 15 and 16 and a crown 17 connected to the same. The paper 35 from which the frame is constructed is also folded to provide the side frame members 12 and 13 with flanges 18 and 19 and a crown 21 between said flanges. The frame members 11 and 12 are further constructed so that the crowns 21 become 40 reduced near the free ends of said frame members, whereby the said flanges may be arranged parallel to one another in overlying position, as illustrated.

The flanges 18 and 19 are provided with openings 23 at their ends which are adapted to register when the parts are assembled and through which the hook 14 is inserted, as will be presently described. The ends of said flanges are cut in 45 the shape of an arc, thereby forming notches 50 55

in the crowns 21, of the frame members 12 and 13, which in conjunction provide a recess 24 in the uppermost portion of the frame 10. The manner of constructing the frame 10 has been 5 fully described in the application of myself and Richard B. Lewis, Jr., Serial Number 112,963, filed November 27, 1936, and forming no particular feature of the instant invention will not be described in detail in this application. As will 10 become apparent, the instant invention may be used with any type of garment hanger having overlying flanges as well as with the construction disclosed in said application for patent.

The hook 14, as shown in Fig. 5, is constructed 15 of wire which is bent as illustrated. This hook has a hook portion 25 which opens outwardly, being formed with a curved part 30 and a free end 26 extending therefrom. The hook portion 25 is adapted to be hooked about a pole, rod or 20 any other suitable support, such as indicated at 27 in Fig. 6. The end 26 of the hook portion 25 is straight and is bent angularly from the curved part 30 to form a bight 28 therebetween which is adapted to occupy the position, shown in Fig. 25 6, when the hook is applied to the support.

Depending from the hook portion 25, is a shank 29 which terminates in a clip 31. Clip 31 consists of two spaced reaches 32 and 33, the reach 32 forming a continuation of the shank 29 and 30 being bent angularly with respect thereto, as indicated at 34. These two reaches are connected together by means of a connecting portion 35. At the upper end of the reach 33, is provided a finger 36, which extends substantially at 35 right angles to the reach 33. The end of the finger 36 terminates in a lug 37 which faces downwardly. The reach 33, of clip 31, is angularly disposed with reference to the reach 32, though situated in a plane parallel with a plane 40 containing said first named reach. These two planes are parallel to the plane of the hook 25 and the connecting portion 35 is at right angles to all of said planes. The reaches 32 and 33 are twisted to such an extent that the distance 45 between the lug 37 and reach 32 is about the same as the connecting portion 35.

The manner of erecting the garment hanger is as follows: The frame 10 comes collapsed with the frame members 12 and 13 folded into overlying positions with respect to the frame member 50 11. When desired for use, the two frame members 12 and 13 are swung outwardly and the flanges 18 and 19 thereof squeezed together at their ends. The flanges 18 and 19, of the two 55 side frame members 12 and 13, are next assembled with one of the flanges of each side frame member disposed between the flanges of the other side frame member, as shown in Fig. 1. The flanges are then adjusted with respect to one 60 another until the various openings 23 register with each other. Due to the forming of the ends of said flanges on a curve, as indicated at 22 in Fig. 1, the notches formed thereby make the recess 24 at the uppermost portion of the frame 65 10 and between the various flanges of the side frame members 12 and 13 as previously described.

In applying the hook, the free end 26 thereof is inserted through the registering openings 23 70 and the hook portion 25 and shank 29 threaded through the same until the parts take the position as shown in Fig. 2. The various flanges are next threaded upon the reach 32 and at the same time are forced into the space 38 between 75 said reaches, as shown in Figs. 3 and 4. As

viewed in Fig. 3 the plane of the hook 25 is at right angles to the plane of the frame 10. After the hook has been thus far applied, the same is manipulated to bring the connecting portion 35 into the openings 23. This is accomplished by 5 drawing the hook further into the said openings and giving the same a twist to bring the aforementioned plane of the hook portion 25 parallel to the plane of the frame 10. At the same time, the lug 38 is forced into the recess 24. This 10 causes the parts to occupy the position, shown in Figs. 1 and 6.

When the hook has been applied to a support, such as designated at 27 in Fig. 6, the bight 28 extends outwardly of the vertical medial plane 15 of the support and connecting portion 35, which plane is designated by the reference numeral 39. I have found that, by constructing the part 30 of the hook portion curved as illustrated and the end 26 thereof straight and forming a bight 20 at the position shown, far greater resistance is afforded to the opening up of the hook than where the bight is in the medial plane, or where a hook curves throughout its extent is utilized.

The advantages of my invention are manifest. 25 The hook is easily applied to the frame of the garment hanger. When once in position, the hook is rigidly secured in place making it extremely easy to apply the hook to the support. By means of the construction of the hook portion 30 of the hook greater strength is procured. The improved hook can be constructed at no additional cost, as compared to hooks previously used for the purpose.

Changes in the specific form of my invention, 35 as herein disclosed, may be made within the scope of what is claimed without departing from the spirit of my invention.

Having described my invention, what I claim as new and desire to protect by Letters Patent is: 40

1. A garment hanger comprising a frame including side frame members having overlapping parts constructed with registering openings therein, a hook having a clip for engagement with said openings, and a hook portion connected therewith, said clip having reaches extending along the sides of said over-lapping parts and a connecting portion therebetween extending through said openings, said reaches being disposed in planes parallel to the plane of said hook 50 portion and being angularly arranged with respect to one another to facilitate application of said hook to said frame members.

2. A garment hanger comprising a frame including side frame members having overlapping 55 parts constructed with registering openings therein, a hook having a clip for engagement with said openings, and a hook portion connected therewith, said clip having reaches extending along the sides of said over-lapping parts and a 60 connecting portion therebetween extending through said openings, said reaches diverging with respect to one another from said connecting portion and a finger formed on the end of one of said reaches and extending inwardly toward the 65 other reach, said clip being adapted to be twisted in application to the hanger to bring said finger out of engagement with said frame.

3. A garment hanger comprising a frame including side frame members having overlapping 70 parts constructed with registering openings therein, a hook having a clip for engagement with said openings, said clip having reaches extending along the sides of the overlapping parts, and a connecting portion therebetween extending through 75

5 said openings, said reaches diverging with respect to one another from said connecting portion and a finger formed on the end of one of said reaches and extending inwardly toward the other reach, 5 said clip being adapted to be twisted in application to the hanger to bring said finger out of engagement with said frame, a shank issuing from the other reach, a hook portion issuing from said shank, said shank being bent at the locality of 10 issuance from said reach to bring the other reach substantially in alignment with the connecting portion of said clip and the center of said hook portion.

15 4. In combination with a cylindrical support, a garment hanger comprising a frame, a hook connected thereto having a hook portion provided with a curved part and a straight end disposed in the plane of said hook portion forming a bight with said curved part, said hook portion 20 being adapted to be applied to said support with the straight part in engagement with the surface of said support to one side of the vertical medial plane of the support and the curved part engaging the cylindrical support at a locality in 25 close proximity to the vertical medial plane of the support and with the bight free from the support.

30 5. A garment hanger comprising a frame including a cross frame member and side frame members pivoted thereto, said side frame members having over-lapping parts constructed with registering openings therein, a hook having a clip for engagement with said parts, said clip comprising spaced parallel reaches adapted to fit 35 against said overlapping parts, a connecting reach between said first named reaches extending through said openings and a finger associated with one of said reaches and overlying the uppermost portion of certain of said side frame members and restraining disengagement of the 40 hook from said frame and a lug on said finger extending between the over-lying parts of said side frame members.

45 6. A garment hanger comprising a frame including a cross frame member and side frame members pivoted thereto, said side frame members being constructed of paper and folded to provide over-lapping flanges, the ends of said flanges being notched at the vicinity of the adjacent portions thereof to provide a recess between said notches when the flanges of one side frame member are assembled with respect to the flanges of the other side frame member, said flanges having registering openings therein, a hook for securing said side frame members together, said hook having a clip provided with a reach extending through said openings and means on said clip extending into the recess formed 50 between said side frame members and holding the hook erected.

7. A garment hanger comprising a frame including a cross frame member and side frame members pivoted thereto, said side frame members being constructed of paper and folded to provide over-lapping flanges, the ends of said flanges being notched at the vicinity of the adjacent portions thereof to provide a recess between said notches when the flanges of one side frame member are assembled with respect to the flanges of the other side frame member, said flanges having registering openings therein, a hook for securing said side frame members together, said hook having a clip constructed with spaced reaches adapted to engage the outermost of the flanges of said side frame members, a reach extending 15 through the openings in said flanges, a finger extending across the uppermost portions of certain of said side frame members and a lug on said finger adapted to enter into the recess formed 20 between said side frame members.

25 8. A garment hanger comprising a frame including a cross frame member and side frame members pivoted thereto, said side frame members having over-lapping parts constructed with registering openings therein, a hook for securing said frame members together, said hook comprising a clip having two spaced reaches and a reach connecting the same, one of said reaches lying along the outer surface of one of the side frame members, said connecting reach extending 30 through said openings and the third reach lying along the opposite outer surface of said frame members, said spaced reaches being disposed in parallel planes and arranged angularly with respect to one another and a finger on said last 35 named reach extending across the uppermost portion of certain of said side frame members.

40 9. A garment hanger comprising a frame including a cross frame member and side frame members pivoted thereto, said side frame members having over-lapping parts constructed with registering openings therein, a hook for securing said frame members together, said hook comprising a hook portion, a shank connected thereto, a clip connected to said shank and having a 45 reach extending downwardly in continuation of said shank and lying along the outer surface of one of said side frame members, a second reach extending through said openings, substantially at right angles to said first reach and issuing from 50 the lowermost portion thereof, a third reach extending upwardly from the second reach and disposed along the opposite outer surface of said frame members in spaced relation with reference to said first reach, and a finger issuing from 55 the upper end of the third reach and extending across the uppermost portions of said side frame members and toward said first reach.

REYNOLDS GUYER. 60
